UNITED STATES PATENT OFFICE

WILLIAM LE ROY BRYANT, OF SPRINGFIELD, VERMONT; BLANCHE B. BRYANT, OF SPRINGFIELD, VERMONT, ADMINISTRATRIX OF SAID WILLIAM LE ROY BRYANT, DECEASED

TRUING MECHANISM FOR GRINDING WHEELS

Original application filed July 20, 1921, Serial No. 486,080. Divided and this application filed December 26, 1925. Serial No. 77,837.

This application is a division of my application entitled "Grinding machine", Serial No. 486,080, filed July 20, 1921, upon which Letters Patent No. 1,575,968 were granted 5 March 9, 1926. The invention relates to improved mechanism for truing grinding wheels which may be used in conjunction with the grinding machine described in the above mentioned application, and in which a 10 better and more stable control is effected than has hitherto been possible. An object of the invention is to provide for a relative reciprocation and transverse feed of the truing mechanism of the grinding wheel, in which 15 one of the instrumentalities is mounted to move toward the other about a fixed center. Other objects of the invention are to provide template or control bars which are interchangeable and adjustable so that the accurate 20 truing of the wheels is not dependent upon the skill of the operator; and to provide for accurate truing of grinding wheels of different shapes, including those wheels which have portions which vary in diameter. 25 In the drawings,—

Fig. 1 represents in front elevation a grinding machine such as is described in detail in my above mentioned Letters Patent No. 1,575,968, and in which my improved truing 30 mechanism is incorporated;

Fig. 2 is a fragmentary end elevation of the upper portion of the grinding machine, which includes the truing mechanism;

Fig. 3 is similar to Fig. 2 but shows the opposite end;

Fig. 4 represents a section through the grinding wheel on a vertical plane transverse to the machine, and illustrates the truing mechanism in operating position;

Fig. 5 illustrates a template or control bar for the truing mechanism, and the mechanism by which said control bar is adjustably and removably supported;

Fig. 6 illustrates in perspective and on an enlarged scale a portion of the bar shown in Fig. 5;

Figs. 7, 8 and 9 represent, on an enlarged scale, sections on the lines 7—7, 8—8, and 50 9—9 of Fig. 5;

Fig. 10 represents a vertical transverse section on the line 10—10 of Fig. 1;

Figs. 11^a and 11^b together represent a longitudinal section on the line 11—11 of Fig. 10, all on a larger scale;

Fig. 12 is a section on the line 12—12 of Figure 11^b;

Figs. 13 to 16 inclusive represent different forms of grinding wheels and the work finished by each, a portion of each wheel being shown. The shape of the work in each case also indicates the contour of the template for truing the corresponding grinding wheel.

Before proceeding to describe the machine illustrated on the drawings thus briefly referred to, I desire to have it understood that the invention is not limited to the particular embodiment thereby illustrated; that many different changes may be made in the machine without departing from the spirit and scope of the invention as defined in the claims, that the phraseology herein employed is for the purpose of description and not of limitation, and that the drawings are more or less conventional.

Proceeding to a description of the illustrated machine,—50 illustrates a hollow bed having suitable front, rear and end walls. On the upper face or table formed by the bed there are two upright end standards 51, 52, 80 which at their upper ends support two parallel bars 53, 54, one of which supports a truing mechanism and the other of which supports the work-holding and rotating mechanism.

The work carrier, on which the work supports are mounted, comprises end arms 55, 56 and a longitudinal bar or table 57 connecting the lower ends of said arms and having a cylindrically concave supporting face 58, as best shown in Figures 10, 11^a and 11^b. Preferably the arms 55, 56 are cast in hollow form for the sake of lightness, and they are clamped to the bar 54. The upper portions of the arms may be split and provided with clamping screws 59. As a result of this construction, the work carrier, by loosening the clamp screws 59, may be adjusted longitudinally of the bar 54 and then clamped rigidly thereto, so that, by moving the bar axially, the work

- carrier may be moved therewith. By mechanism, which I shall subsequently explain, the bar may be moved manually or automatically in an axial direction for the purpose of effecting either an adjustment or a reciprocation of the work in lines parallel to the axis of the work. As shown in Figures 11^a and 11^b, the uprights 51, 52 may be provided with tapered bushings 60, 61, in which the bar 54 is journaled and in which it may be moved longitudinally. These tapered bushings may be adjusted to compensate for wear by nuts 62, 63, abutting against the inner faces of the uprights. By mechanism, subsequently to be explained, the work carrier and its supporting bar 54 may be swung about the axis of the bar 54 for the purpose of advancing the work to and withdrawing it from the grinding wheel.
- 20 The grinding wheel may be of any desired shape according to the work to be ground. In the form shown in Fig. 14, it comprises three abrading members 91, 92 and 93, which may be of different kinds of grinding material, if desired. These may be provided with spacing and clamping members of any convenient type to secure them to a shaft 65 for rotation.

Although a driving pulley may be mounted directly on the shaft 65 to drive the grinding wheel, I prefer to avoid the resulting bending stresses on the shaft due to the lateral pull of the belt on a pulley, which stresses cause more rapid wear on the shaft bearings. A shaft 115 is therefore mounted coaxially with the shaft 65 and is connected thereto by a suitable universal joint as shown and described in Letters Patent No. 1,575,968. A pulley 114 is mounted on the shaft 115 and driven from any suitable source of power, as by a belt 113. The grinding wheel is also preferably mounted in such a way that it can be adjusted with its carrier 66 towards or from the work carrier, as by rotation of an abutment screw 68.

By inspection of Figure 10, it will be observed that the work carrier depends normally from the bar 54 in front of the grinding wheel. The movement of the work, which is carried by the work carrier, is in a curvilinear path towards or from the grinding wheel, whereas the grinding wheel and its carrier are adjusted in rectilinear paths towards or from the work carrier. The adjustment of the grinding wheel carriage is ordinarily effected only when the machine is being set up for work of a relatively large or a relatively small diameter, or when the grinding wheel of one size is substituted for a grinding wheel of another size, or where a grinding wheel has been reduced in diameter to a considerable extent by use. The work carrier, however, is swung about its axis to effect a feeding movement of the work towards the grinding wheel or its withdrawal from grinding position.

The work carrier may be reciprocated longitudinally of the work axis, and thus longitudinally of the bar 54 whose axis is parallel to that of the work axis, so as to effect an axial movement of the work while it is in engagement with the grinding wheel. In some cases, however, it is not desirable to have this longitudinal movement of the work carrier, in which event the mechanism for effecting the reciprocation of the work support is rendered inactive. The entire work carrier may be adjusted longitudinally of the work axis so as to locate any predetermined part of the work in proper relation to the grinding wheel. To this end, the bar 54, as shown in Fig. 11^a, is provided with rack teeth 162 which extend part way around its periphery. With the rack thus formed, there is engaged a pinion 163 secured on a shaft 164 journaled in a block 165 into which the end of the bar 54 projects. The end of the shaft 164 is angular in cross section, as shown at 166 in Fig. 3, so that, by applying a wrench or handle thereto, the pinion 163 may be rotated in one direction or the other to move the bar 54 longitudinally of its axis, the block in the meantime being held against movement. I also provide means by which the block itself may be rocked or reciprocated back and forth to effect the automatic longitudinal reciprocation of the work carrier. To accomplish this result, an arm or lever 167 is pivoted on a pintle 168 mounted in lugs 169 projecting from the upright 52 of the frame. This lever or arm 167 is provided with an upwardly projecting yoke 170 which embraces a pin 171 inserted in the block 165 and located almost directly above the pintle 168. Consequently, by rocking the lever 167 about the axis of the pivot or pintle 168, the block 165 and the bar 54 may be reciprocated. The lever 167 is automatically oscillated about its axis by any suitable mechanism driven from the main power shaft. As described in Letters Patent No. 1,575,968, such mechanism is preferably provided with a clutch device such that when the operating handle is operated to disengage the clutch, the latter will remain in engagement until the work carrier reaches the right hand end of its movement as viewed in Fig. 1. This is desirable particularly when shouldered work is being ground as the larger grinding wheels are to the right of one facing the machine. It is furthermore desirable because, as will be subsequently explained, the work carrier carries the control template or bar which governs the action of the truing mechanism on the wheel, and it is also desirable that the work carrier should be stopped always at the same point in truing the wheel for any particular grinding operation.

For effecting a relative transverse feed of the work and the grinding wheel, I employ a single-speed automatic feed mechanism by which the work and the grinding wheel are

brought into grinding relation and continued in that relation until the work has been reduced to the desired diameter, after which the work and the tool are separated, whereupon the feed is automatically discontinued. 5 Provision is made, however, by which the operator may manually effect a feeding or withdrawing movement of the movable element. The transverse feeding mechanisms act 10 through a slide 198 which is mounted on the bed of the machine and against an end of which rests a guide bar or template 197 mounted on a dependent portion 196 of the longitudinal member 57 of the work carrier. 15 Since the work carrier is pivotally swung on an axis, the slide 198 acts as an adjustable stop to limit the outward swing of the work carrier away from the grinding wheel.

For the reciprocation of certain parts of the machine, such as the sliding shaft 228, 20 fluid-actuated pistons may be provided which can be readily controlled by suitable valves. Any suitable source of fluid pressure may be used. With my grinding machine I have provided a pressure system comprising a reservoir 240 for fluid, and a rotary pump, the casting of which is indicated at 242, from which conduits are led to the various pistons and control valves. Relief valves are also provided to prevent excessive pressure in the 25 supply conduits. This pressure system as well as the other parts of the machine, which have been mentioned are fully described in Letters Patent No. 1,575,968, previously referred to.

The present invention involves one of the salient features of the grinding machine, that is, the truing mechanism for the grinding wheels. The dressing tool is mounted in a 40 swinging arm which is normally in inactive position but which may be swung downwardly so as to bring the dressing tool into operative relation to the grinding wheel. The dressing tool is indicated at 300 and it is 45 adjustably clamped in a swinging arm 301, the hub 302 of which is rigidly secured to the bar 53, to which reference has previously been made. This bar is adapted to oscillate in bushings 303, 304, placed in bearings in 50 the upright standards 51, 52, and is also adapted to slide therein. To protect the bearings, the bar 53 is provided with two sets of telescoping sleeves, 305, 306. In each case, the sleeve 306 is screwed into the threaded aperture in the upright or standard, and the sleeve 305 can slide back and forth with the bar 53. At one end, the bar 53 has a weighted arm 307 keyed thereto, and between the hub of this arm and a shoulder 308 on 55 the bar there is placed a second weighted lever 309. The hubs of these two levers have spaced shoulders 310, 311, adapted to engage when one has moved to a limited extent relatively to the other. Normally, when the 60 dressing tool is not in operation, the weighted

arms 307, 309 hang downwardly and hold the arm 301 substantially upright in the position shown in Figures 1 and 3. The operator, however, standing in front of the machine, may manually grasp the arm and 70 swing it forwardly and downwardly. During the first portion of this movement, the partial rotation of the bar 53 swings the weighted arm 307 rearwardly and upwardly until the shoulders 310, 311 on the hubs of the two weighted arms engage, and thereafter 75 the weighted arm 309 will be swung rearwardly and upwardly until it reaches the position shown in Fig. 4, in which position the dressing tool is engaged with the grinding wheel. The bar 53 may now be reciprocated under the control of the operator. Any suitable mechanism for effecting its reciprocation is employed, but preferably, inasmuch as I employ other mechanism which 80 is controlled by fluid pressure, I also utilize this pressure for moving the dressing tool bar. To this end, a casing 312 is screwed to the bearing at the upper end of the upright 52. The end of the bar 53 is enlarged to form a cylinder 313, the inner end of which may be closed by a plug 314. A stationary piston 315 is located in the cylinder thus provided and a stationary extension or piston rod 316 extends through a stuffing box located in the head 317 at the end of the cylinder. The outer end of this piston rod is screwed into the end of the casing 312. Conduits 318, 319 extend through the piston rod, the former connecting with the lefthand end of the cylinder and the latter connecting with the righthand end of the cylinder, as best shown in Fig. 11a. When the fluid is delivered through the conduit 318, the piston being 90 stationary, the entire bar 53 is moved to the left, and, of course, when fluid is delivered through the conduit 319, the bar 53 is moved to the right so that the dressing tool may be caused to traverse the face of the grinding wheel. Suitable pipes 320, 321 connect the conduits 318, 319, respectively, with a valve mechanism contained in the casing 326 and fully described in Letters Patent No. 1,575,968. A handle 340 is attached to the valve, by manipulation of which the operator 95 may move the valve in one direction or the other to cause the corresponding movement of the bar 53 and the dressing tool carried thereby. 100

When the truing tool is operating on the grinding wheel, it may be guided in any desired path by the use of a control bar or template which is preferably supported on the work carrier. Referring now to Figures 110 4 to 8, and 10, it will be noted that, on the front side of the longitudinal bar 57 which forms a portion of the work carrier, there is an upright longitudinal flange 350, and in the angle formed by this flange there are secured two blocks 351, 352, which constitute 115 120 125 130

portions of a holding mechanism for the control bar or template. In these blocks there are arranged two center pins 353, 354. The block or holder 351 is split so that the center pin 353 may be clamped in place by the screw 355 after the center pin has been adjusted to proper position. The center pin 354 is seated in a socket in the holder 352, which is also split (as shown in Fig. 7) so that the split portions may be drawn together by a screw 356 to clamp the center pin. A spring 357 is seated in the socket and bears against the shoulder on the center pin, as best shown in Fig. 5. By slightly loosening the clamp, the head 358 on the end of the center pin may be grasped and the center pin moved to the right to release the control bar which was previously engaged thereby. A control bar of any suitable form may be placed in the holders and locked rigidly in place so as to guide the dressing tool arm as it is reciprocated axially of the bar 53. The control bar may be straight, shouldered, convexly or concavely curved, or tapered, as may be desired. Preferably, although not necessarily, it is circular in cross section. I have shown in Fig. 5 a control bar which is indicated at 359 and which has centering recesses 360, 361 at its ends to receive the center pins 353, 354. The ends of the control bar rest on flat faces 362, 362 (shown in plan view in Fig. 5) on which the center pin holders 351, 352 are secured, and the sides of the end portions of the control bar rest against abutment screws 363, 364, which are passed through the flange 350 of the work carrier. The abutment screw 363 has a relatively coarse thread and it is locked in position by a set screw 365. The screw 364 has a fine thread and is screwed into a threaded sleeve 366 inserted in a flange 350. The end of this screw has a knurled head 367 by which it may be rotated. In practice, the center pin 354 being drawn to the right in Fig. 5, the control bar is placed in position as shown, so that its ends rest on the flat faces 362 and its sides against the screws 363, 364, after which the center pin 358 is released by the operator and is forced by its spring into engagement with the socket 361 at the end of the bar. Each end of the bar is thus engaged by a three-point bearing and is held accurately in position. The clamping screws 355, 356 may be set tight to hold the center pins in position. Ordinarily, the pressure of the spring 357 is sufficient to cause the center pins to grip the control bar and hold it accurately in position without tightening the clamping screw 356. The holding mechanism for the control bar is capable of an exceedingly fine adjustment without distorting the control bar. The swinging arm 301, which carries the dressing tool 300, is formed at its end with a bearing 369 in which a thrust pin 368 is arranged so that the end of

the thrust pin may project beyond the arm and be brought against the rear side of the control bar 359, as shown in Fig. 4. The arm is of such length that it can be swung over or past the control bar, and, to permit this, the pin 368 must be partially withdrawn so that its projecting end is substantially flush with the end of the arm. The pin is provided with a knurled head 370 which may be grasped by the operator for this purpose. The bearing for this thrust pin is split, as shown in Fig. 2, and a clamping screw 371 may be used to draw the portions of the bearing together to clamp the thrust pin in either its advanced or retracted position. When the operator desires to dress the grinding wheel, the arm 301 is moved from the position shown in Fig. 3 forwardly and downwardly, and the thrust pin 368 is retracted to permit the arm to pass the control bar 359. Thereafter the operator forces the thrust pin downwardly so that its end engages the rear side of the control bar, as shown in Figure 4. When in this position the counterweight 309 presses the thrust pin 368 against the control bar 359. The operator then by hand operates the feed mechanism of the work carrier to bring the dressing tool into engagement with the grinding wheel, and, by manipulation of the valve handle 340, causes the dressing tool bar 53 to be reciprocated, whereby the dressing tool traverses the face of the grinding wheel. The control bar corresponds to the shape of the finished work so that the wheel is dressed to impart that shape to a new piece of work. For example, in Figs. 13 to 16 inclusive, I have illustrated different pieces of work, and the control bars for dressing the wheels, by which these pieces of work are finished, correspond to the pieces as illustrated. Where the grinding wheel consists of several sections which vary in diameter, as, for example, in Figure 14, there are shoulders between the several sections, and the thrust pin on the dressing tool arm could not slide back and forth on the shouldered control bar. I provide, however, a shouldered control bar in which this may be accomplished. In Figures 5 and 6, I have shown the control bar as being provided with the three different diameters *a*, *b* and *c*, separated by the shoulders *d* and *e*. In the smaller section *c* and in the intermediate section *b*, I introduce pins 372, 373, which are semi-cylindrical. The end of each pin is flush with the next section of a larger diameter, but it is also provided with inclined faces 374, 374, by which the end of the thrust pin may be guided from the periphery of one section *c* for example, to the next section *b* for example, and thence to the section *a*. To accomplish this result, assuming that the thrust pin 368 is moving to the left in Figure 5, it continues this movement until it

engages the shoulder *e*. The operator then by hand rotates the control bar about its axis to bring the beveled pin 372 under the thrust pin and thus thrust it rearwardly far enough until it can ride on the section *c* of the control bar. The thrust pin then continues its movement to the left until it engages the shoulder *d*, whereupon the operator again rocks the control bar to bring the pin 373 under the thrust pin and again swing the thrust pin rearwardly far enough until it can ride on the section *a*. When the thrust pin is moving in the opposite direction or to the right, it may drop off of the shoulder to the next diametrically smaller section without doing any damage. It will be remembered that the dressing tool bar 53 is moved by fluid pressure from the pump, but, inasmuch as the relief valve mechanism previously described is included in the hydraulic system, the thrust pin 368 may engage one of the shoulders *d* or *e* and be arrested without damage. A very decided advantage is thus achieved by the employment of a yielding mechanism for operating the dressing tool.

Having thus described the nature of my said invention and described a way of making and using the same, although without attempting to set forth all of the forms in which it may be made or all of its modes of use, what I claim is:

1. A grinding machine comprising a bed, a grinding wheel, a bar journaled in the bed parallel with the axis of the grinding wheel, a dressing tool carrier hung on said bar, and having an inoperative position above said wheel, said carrier being movable forwardly and downwardly about the axis of said bar from said inoperative position to bring the dressing tool into engagement with said wheel, and means for moving said tool carrier lengthwise of the axis of said bar.

2. A grinding machine comprising a bed, a grinding wheel, an arm pivoted at one end to swing about an axis substantially parallel to the axis of the grinding wheel, said arm having adjacent its other end means for holding a dressing tool, means for moving said tool carrier lengthwise of its axis, and a template engageable by the tool-holding end of said arm, said template extending parallel to said axis and held against longitudinal movement along which said arm may slide for controlling the pivotal movement of said arm.

3. A grinding machine comprising a bed, a grinding wheel, an arm pivoted at one end to swing about an axis substantially parallel to the axis of the grinding wheel, said arm having adjacent its other end means for holding a dressing tool, a template engageable by the tool holding end of said arm, said template being arranged parallel to said axis for controlling the pivotal movement of said

arm, and means for effecting a relative movement of said grinding wheel, arm and template longitudinally of said axis.

4. A grinding machine comprising a bed, a grinding wheel, a pivoted dressing tool carrier movable about an axis substantially parallel to the axis of the grinding wheel to present a tool against the periphery of said wheel, means for moving said tool carrier lengthwise of its axis, a template for controlling the pivotal movement of said tool carrier and hence the distance of the tool from the axis of the wheel, and mechanism for effecting a relative movement of said wheel and template in lines transverse to the axis of said wheel, whereby the template-controlled distance between the tool and the axis of the wheel may be modified.

5. A grinding machine comprising a bed, a grinding wheel, a pivoted dressing tool carrier movable about an axis substantially parallel to the axis of the grinding wheel to present a tool against the periphery of the wheel, means for moving said tool carrier lengthwise of its axis, a template for controlling the pivotal movement of said tool carrier and hence the distance between the tool and the axis of the wheel, and manually-operated feed mechanism for feeding said template toward and from said wheel, whereby the action of the template may be modified without altering its shape.

6. A grinding machine comprising a bed, a grinding wheel thereon, a dressing tool carrier pivoted to the bed, counterbalancing weights connected to said tool carrier for holding it normally in a raised inactive position, and mechanism normally clear of said tool carrier with which said tool carrier may be engaged, when swung into downward active position, for feeding a tool carried thereby to the grinding wheel.

7. A grinding machine comprising a bed, a grinding wheel thereon, a work carrier, a dressing tool carrier pivoted to the bed and swingable to present a dressing tool against the periphery of said wheel, and means for engaging the free end of said tool carrier with said work carrier to hold said tool in operative position against said wheel.

8. A grinding machine comprising a bed, a grinding wheel thereon, a dressing tool carrier pivoted to the bed, a work carrier pivoted to the bed and adjustable toward and from said wheel, and means for guiding the tool carrier comprising means for engaging the tool carrier with said work carrier.

9. A grinding machine comprising a bed, a grinding wheel thereon, a dressing tool carrier pivoted to the bed, a work carrier pivoted to the bed and adjustable toward and from said wheel, means for guiding the tool carrier comprising means for engaging the tool carrier with said work carrier, and means

- for moving said tool carrier longitudinally of its axis relatively to said grinding wheel.
10. A grinding machine comprising a bed, a grinding wheel thereon, a dressing tool carrier pivoted to the bed for movement toward and from said grinding wheel, a template extending parallel to the pivot axis of said carrier, means for detachably engaging said carrier with said template, means for normally holding said carrier in an inactive position out of engagement with said template, and means for causing relative movement between the tool carrier and template longitudinally of said axis.
15. 11. A grinding machine comprising a bed, a grinding wheel thereon, a dressing tool carrier pivoted to the bed for support and for movement toward and from said grinding wheel, a template extending parallel to the pivot axis of said carrier, means for detachably engaging said carrier with said template, a carrier pivoted to said bed on an axis parallel to that of said tool carrier and independently of said tool carrier support for supporting said template, and means for moving said template carrier about its pivot.
20. 12. A grinding machine comprising a bed, a grinding wheel thereon, a dressing tool carrier pivoted to the bed for support and for movement toward and from said grinding wheel, a template extending parallel to the pivot axis of said carrier, means for detachably engaging said carrier with said template, means for reciprocating said tool carrier endwise of said template, a carrier movably supported by said bed independently of said tool carrier support for carrying said template, and feed mechanism for said template carrier.
25. 13. A grinding machine comprising a bed, a grinding wheel, a work carrier pivoted to move toward and from the grinding wheel, feed mechanism therefor, a template on said carrier, a bar mounted on said bed, a swinging arm attached to said bar and adapted to be engaged with said template, a dressing tool carried by said arm, and means for reciprocating said bar to move said arm endwise of said template.
30. 14. In a grinding machine, a grinding wheel, a movable dressing tool carrier, and a square-shouldered control bar or template with which said carrier may be engaged and along which it may be moved, said bar having inclined faces at the shoulders for guiding the tool carrier past said shoulders, said bar being movable to engage one of said faces with said tool carrier when the latter is in engagement with the adjacent shoulder.
35. 15. In a grinding machine, a grinding wheel, a movable dressing tool carrier, and a revolvable shouldered control bar or template with which said carrier may be engaged and along which it may be moved, said bar or template being circular in cross section with inclined faces at the shoulders.
40. 16. A grinding machine comprising a grinding wheel, a pivoted dressing tool carrier movable toward and from the said wheel and also across the face thereof, a relatively stationary control bar or template approximately parallel to said face, and a latch on said carrier normally clear of said template for detachably engaging said carrier with said control bar or template and for sliding along said control bar or template.
45. 17. A grinding machine comprising a bed, a grinding wheel supported thereon, a relatively stationary control bar or template extending across the face of said wheel, an arm pivoted to said bed so that its free end may be engaged with and disengaged from said control bar or template, and a dressing tool fixed in said arm for engagement with said face of said wheel.
50. 18. A grinding machine comprising a bed, a grinding wheel supported thereon, a relatively stationary control bar or template extending across the face of said wheel, an arm pivoted to said bed so that its free end may be engaged with and disengaged from said control bar or template, a dressing tool fixed in said arm for engagement with said face of said wheel, and means for moving said arm lengthwise of its pivotal axis.
55. 19. In a grinding machine, a shouldered grinding wheel, a dressing tool carrier movable across the faces of said wheel and toward and from the same, a shouldered control bar along which said carrier is movable, yielding means for moving said carrier along said bar, and means for holding said control bar to permit a rotative movement thereof about a longitudinal axis, said bar having inclined faces at the shoulders to raise the carrier from one portion of the bar to another portion thereof when so rotated.
60. 20. A grinding machine comprising a bed, a grinding wheel, an arm swingable about an axis substantially parallel to the axis of the grinding wheel, said arm having an end thereof remote from said axis, means on said arm adjacent to said remote end for holding a dressing tool, a template engageable by the tool-holding end of said arm and arranged parallel to said axis for controlling the pivotal movement of said arm, and means for moving said arm longitudinally relatively to said template and said wheel.
65. In testimony whereof I have affixed my signature.
- WILLIAM LE ROY BRYANT.
